GEORGE W. DUNHAM, OF NEW HAVEN, CONNECTICUT, ASSIGNOR TO THE WHIRLDY CORPORATION, OF NEW HAVEN, CONNECTICUT, A CORPORATION OF NEW YORK

WASHING MACHINE

Application filed November 9, 1928. Serial No. 318,177.

The invention relates in general to laundry machines, and more particularly to a washing machine of the centrifugal drying type.

According to one form of the invention the machine comprises an outer container or tank supporting suitable driving devices. Projecting upwardly from the bottom of the tank is a hollow pedestal upon which is mounted the hub of a laundry receptacle. Disposed within the hollow pedestal is a pair of concentric shafts, one of which has imparted thereto by the driving devices an oscillatory motion for washing, and the other a continuous rotary motion for centrifugal drying. Suitable clutching devices are provided at the top of the hub for selectively connecting the receptacle to the shafts without the interposition of any separate movable members.

The invention also consists in certain new and original features of construction and combinations of parts hereinafter set forth and claimed.

Although the novel features which are believed to be characteristic of this invention will be particularly pointed out in the claims appended hereto, the invention itself, as to its objects and advantages, the mode of its operation and the manner of its organization may be better understood by referring to the following description taken in connection with the accompanying drawings forming a part thereof, in which

Fig. 1 is an elevation of the machine with parts in section;

Fig. 2 is a vertical section on the line 2—2 of Fig. 1 through the clutch showing the receptacle at its lower or washing position;

Fig. 3 is a view similar to Fig. 2 showing the receptacle at its upper or drying position; and

Fig. 4 is a plan section of the clutch taken on the line 4—4 of Fig. 3.

In the following description and in the claims parts will be identified by specific names for convenience, but they are intended to be as generic in their application to similar parts as the art will permit.

Like reference characters denote like parts in the several figures of the drawings.

In the drawings accompanying and forming part of this specification, a practical commercial embodiment of the invention is shown, but as such illustration is primarily for purposes of disclosure, it will be understood that the structure may be modified in various respects without departure from the broad spirit and scope of the invention as hereinafter defined and claimed.

Referring to the drawings, the laundry machine comprises in general a container or tank 1 having a pair of handles 2 and a cover 3 removably fitting on the top of the tank. The tank is supported by a base ring 4 which encloses the drive motor 5 and gear box 6 which latter are suspended from the bottom 10 of the tank. Secured to the center of the tank in a center opening is a fitting 11 to which is secured an upstanding hollow pedestal 59. Disposed within the hollow pedestal is a pair of concentric shafts 57 and 58 driven by the gearing in the gear box 6. The tubular shaft 58 has imparted thereto an oscillatory rotary motion for washing and the solid shaft 57 has imparted thereto a continuous rotary motion for centrifugal drying.

Journalled on the hollow pedestal is a receptacle 7 having paddles or blades 8 therein for aiding in agitating the laundry. The receptacle comprises a foraminous outer wall 105, a solid bottom wall 106, a hub 107, and guard ring 108. These members may be made of sheet metal and may be connected together in any of the well known ways for connecting sheet members such as simple lap joints, double lock joints, welding, etc.

It will be understood that the details of construction of the gearing in the gear box, the mounting of the motor, stabilizing support for the tank and the construction of the receptacle are omitted for the sake of clearness, these constructions being disclosed at length in prior application Serial No. 308,316 filed Sept. 25, 1928.

The upper end of the pedestal 59 is provided with a bearing sleeve 101 (Figs. 2

and 3) for the upper end of the tubular shaft 58 and the inside of the tubular shaft has a bearing sleeve 102 for the upper end of the solid shaft 57. Near the lower end 5 of the pedestal 59 there is provided a bearing sleeve 103 having longitudinal grooves to prevent trapping of water inside the hub 107. The upper end of the pedestal has a conical ring 104 which does not bear against 10 the hub of the receptacle for either washing or drying but which assists positioning the receptacle on the pedestal when it is replaced after removal for cleaning or other purposes.

15 For selectively connecting the receptacle to the drive shafts 57 and 58 a clutch construction is provided. The upper end of the tubular shaft 58 is provided with splines 111 and a groove in which a lock ring 112 20 is sprung. The upper end of the solid shaft 57 has a sleeve 113 pinned thereto, this sleeve having splines 114 the same radial dimensions as the splines 111. The upper end of the hub 107 is provided with 25 a sleeve-like fitting 115 having splines 215 which selectively engage the splines 111 and 114. This fitting has a recess in which is disposed a ring 116. This ring has secured thereto a push button 117 projecting out 30 through a hole in the sleeve member 115 and in the hub 107. The sleeve member is provided with a second hole in which is disposed a coil spring 118 acting between the ring 116 and the hub 107. A cover 119 having 35 a recess to accommodate the splines 114 fits in the sleeve 115, is keyed thereto, and is provided with a pair of guides 120 on its lower edge to guide the ring 116 in a direction parallel to the direction of the push 40 button and spring. A suitable locking ring 121 is sprung in a groove in the sleeve 115 to hold the cover 119 in position. It will be noted that the splines 111 are long enough to engage the ring 116 when the receptacle 45 is connected to the tubular shaft, thus avoiding rubbing contact between the ring 116 and the sleeve 113.

It will be seen that in the position shown 50 in Fig. 2 the receptacle is connected to the tubular shaft for washing and in the position shown in Fig. 3 it is connected to the solid shaft for drying. The tubular shaft is provided with a guard ring or washer 122 overhanging the pedestal to prevent 55 water from accidentally getting down between the tubular shaft and pedestal.

It will be noted from Figs. 2 and 3 that 60 the lock ring 112 constitutes an abutment against which the sleeve 115 rests when the receptacle is in the washing position, and that the upper end of inner shaft 57 constitutes an abutment against which the ring 116 rests when the receptacle is in the drying position.

65 From the above it will be seen that, when

the clutch and receptacle is in either position, the drive is direct from the drive shaft to the receptacle without the interposition of loose or movable members. In other words, all parts necessary to secure connection from one of the drive shafts to the receptacle are either unitary with the drive shaft or with the receptacle. The hub 107 and concentric shafts 57 and 58 are coaxial. Therefore to shift from the washing to the drying position it is only necessary to shift the receptacle 7 bodily, axially. Furthermore, it will be seen that the receptacle is journalled on but one bearing 103 located on the pedestal near the bottom thereof and is supported at 80 its other end on the shaft to which it is selectively connected.

To use the machine the tank is filled with water and the receptacle with the articles to be washed. The clutch is set to connect the tubular shaft to the receptacle. The oscillatory rotary motion of the tubular shaft is imparted to the receptacle and the clothes are washed. To dry the clothes the water is drained from the tank and the receptacle is raised and connected to the inner shaft. The continuous rotary motion of this shaft imparts a similar motion to the receptacle and the clothes are dried.

While certain novel features of the invention have been shown and described and are pointed out in the annexed claims, it will be understood that various omissions, substitutions and changes in the forms and details of the device illustrated and in its 100 operation may be made by those skilled in the art without departing from the spirit of the invention.

What is claimed is:

1. In a laundry machine, a tank, a hollow pedestal in said tank, a tubular shaft in said pedestal having a bearing surface engaging the upper end of said pedestal, an inner shaft in said tubular shaft having a bearing surface engaging the upper end of said tubular shaft, each shaft having a set of splines, said sets being axially spaced and of equal transverse dimension, a bearing sleeve secured around the lower part of said pedestal, a laundry receptacle having an upstanding hub, said hub having a sleeve at its upper end having splines to selectively engage said first splines, said hub having an inner bearing surface to engage said bearing sleeve, and means for imparting different motions to said shafts.

2. In a laundry machine, a tank, a hollow pedestal in said tank, a tubular shaft in said pedestal having a bearing surface engaging the upper end of said pedestal, an inner shaft in said tubular shaft having a bearing surface engaging the upper end of said tubular shaft, each shaft having a set of splines, said sets being axially spaced and of equal transverse dimension, a bearing

sleeve secured around the lower part of said pedestal and having axial grooves, a centering ring having a conical surface secured to the outer face of the upper end of said pedestal, a washer secured to said tubular shaft and overhanging the upper end of said pedestal, a laundry receptacle having an upstanding hub, said hub having a sleeve at its upper end having splines to selectively engage said first splines, said hub having an inner bearing surface to engage said bearing sleeve, and means for imparting different motions to said shafts.

3. In an apparatus of the character described, closed, a hollow support, rotatable concentric shafts within said support, each of said shafts having a non-circular portion, a driven element comprising a hollow member surrounding said support and slidably thereon, 20 said member having a cooperating non-circular portion for selective engagement with said first-mentioned non-circular portions, said shafts having abutments transverse of their axes, means supporting axially said 25 driven element on said abutments when engaged selectively with said shafts, and means for imparting different motions to said shafts.

4. In a machine of the character described, 30 a pedestal, a plurality of concentric shafts having independent movements, within said pedestal, an article-receiving receptacle, means whereby said receptacle at one part thereof, when axially moved, may selectively engage one or the other of said shafts for both lateral and axial support, and means whereby said receptacle also has bearing relation with said pedestal at a second part spaced from said first part.

40 5. In a machine of the character described, an upstanding hollow pedestal, a plurality of shafts in said pedestal, an article-receiving receptacle having an upstanding hub, means whereby said hub may selectively engage one or the other of said shafts for both lateral and vertical support, said hub having bearing on said pedestal near the lower end of said hub, and means for imparting motions to said shafts.

50 6. In a washing machine, a tank, an upstanding hollow pedestal in said tank, a plurality of concentric shafts in said pedestal, an article-receiving receptacle having an upstanding hub, means whereby said hub when axially moved may selectively engage one or the other of said shafts for both lateral and vertical support, said hub having bearing on said pedestal near the lower end of said hub, and means for imparting different motions to said shafts.

7. In a laundry machine, a tank, a hollow pedestal disposed in said tank, concentric shafts in said pedestal, a sleeve on the inner shaft, said sleeve and outer shaft each having splines of the same transverse dimension,

but spaced from each other, a clothes receptacle having an upstanding hub, a second sleeve secured in said hub and having splines adapted to engage selectively with either of said first mentioned splines, an abutment on said outer shaft at the lower end of the splines thereon, said second sleeve having a recess and diametrically opposed openings, a movable lock ring in said recess, a spring in one of said openings between said ring and hub, a push button in the other of said openings and secured to said ring, a cap fitting in said sleeve to confine said ring, depending guides for said ring secured to said cap, a lock wire disposed in a groove in said sleeve to hold said cap in position, whereby said lock ring may engage the upper end of said inner shaft to connect said inner shaft and receptacle and may surround said shafts when said outer shaft is connected to said receptacle.

8. In a laundry machine, a tank, a hollow pedestal disposed in said tank, concentric shafts in said pedestal, a sleeve on the inner shaft, said sleeve and outer shaft each having splines of the same transverse dimension, but spaced from each other, a clothes receptacle having an upstanding hub, a second sleeve secured in said hub and having splines adapted to engage selectively with either of said first-mentioned splines, an abutment on said outer shaft at the lower end of the splines thereon, said second sleeve having a recess and diametrically opposed openings, a movable lock ring in said recess, a spring in one of said openings between said ring and hub, a push button in the other of said openings and secured to said ring, whereby said lock ring may engage the upper end of said inner shaft to connect said inner shaft and receptacle and may surround said shafts when said outer shaft is connected to said receptacle.

9. In a laundry machine, a tank, a hollow pedestal disposed in said tank, concentric shafts in said pedestal, said inner and outer shafts each having splines of the same transverse dimension, but spaced from each other, a clothes receptacle having an upstanding hub, said hub having splines adapted to engage selectively with said first-mentioned splines, an abutment on said outer shaft at the lower end of the splines thereon, said hub having a recess and diametrically opposed openings, a lock ring in said recess, a spring in one of said openings, a push button in the other of said openings and secured to said ring, whereby said lock ring may engage the upper end of said inner shaft to connect said inner shaft and receptacle and may surround said shafts when said outer shaft is connected to said receptacle.

10. In a combined clothes washing ma-

chine and centrifugal extractor, a continuously rotating machine element, an oscillatory machine element coaxial with said continuously rotating machine element, a clothes basket, first clutch means between said basket and said rotating machine element, second clutch means between said basket and said oscillatory machine element, and means for selectively engaging said clutch means by axially and bodily shifting said clothes basket.

11. In a laundry machine, a tank, a receptacle journalled on said tank and having a vertical rotary member secured thereto, a gear box under said tank, a continuously rotating shaft and an oscillatory rotary shaft driven from said gear box, said shafts and rotary member all being coaxial clutch elements connected to each of said shafts, and rotary member, the clutch elements on said drive shafts being spaced axially, said receptacle and the clutch elements on said rotary member being shiftable axially to selectively engage the clutch elements on said drive shafts for washing and drying operations, respectively.

12. In a combined washing and drying machine, a pair of coaxial rotary machine elements, means for imparting a continuous rotary motion to one of said elements for drying purposes, means for imparting an oscillatory rotary motion to the other of said elements for washing purposes, a clothes basket, clutch devices fixedly secured to said rotary machine elements respectively, co-operating clutch devices fixedly secured to said basket, and means whereby the clutch devices on said basket may be selectively and directly engaged with said first mentioned clutch devices by axially shifting said basket with respect to said elements.

In testimony whereof I have hereunto set my hand.

GEORGE W. DUNHAM.
